UNITED STATES PATENT OFFICE.

HERMAN IGNACIO WIECHERS, OF LEON, MEXICO.

TELEPHONE-PAY-STATION CABINET.

1,019,574.

Specification of Letters Patent. Patented Mar. 5, 1912.

Application filed March 29, 1911. Serial No. 617,636.

To all whom it may concern:

Be it known that I, HERMAN IGNACIO WIECHERS, a citizen of Mexico, residing at Leon, in the Province of Gto and Republic of Mexico, have invented new and useful Improvements in Telephone-Pay-Station Cabinets, of which the following is a specification.

My invention relates to telephone pay stations and more particularly to a device adapted to hold the telephone instrument but permitting access to the same upon depositing a coin of the necessary denomination in a slot.

As is well known telephone companies lose thousands of dollars every year, because of the fact that there is no absolute certain way in which the operator at the central office can determine whether or not the person using the instrument at the pay station has deposited the proper coin.

It is an object of my invention to overcome this difficulty and to provide a device which will prevent access being had to the instrument until the coin has been actually deposited and registered at the central office.

Another object of my invention is to provide a device of the above nature which shall be absolutely certain in its operation, and which shall have means whereby an indicator in the central office is caused to show the exact denomination of the coin which has been dropped in the slot, in order to gain access to the instrument and which shall also retain such instrument in a slot compartment, until a coin of some denomination has been deposited.

With the foregoing and other objects in view my invention consists in such details of construction and in the arrangement and combination of parts as will be hereinafter more fully described and specifically pointed out in the appended claims.

In describing my invention in detail, reference will be had to the accompanying drawings wherein like characters denote like or corresponding parts throughout the several views, and in which:

Figure 1 is a view of my improved device in front elevation. Fig. 2 is a vertical sectional view taken on the line 2--2 of Fig. 1 looking in the direction of the arrow. Fig. 3 is a view similar to Fig. 2, but taken on the line 3--3 looking in the direction of the arrow. Fig. 4 is a horizontal sectional view

of Fig. 1. Fig. 5 is a detailed view showing the method of closing the circuit so as to indicate to the central office the denomination of the coin deposited. Fig. 6 is a detailed view showing the construction of one of the slots and the coin-slide leading therefrom. Fig. 7 is a detailed view in perspective, showing the unlocking mechanism of the door. Fig. 8 is a perspective view of the plate which closes the coin slots. Fig. 9 is a diagrammatical view showing one manner of wiring my invention whereby the electric circuits will indicate to the central office the denomination of the coin deposited, and Fig. 10 is a detailed view showing the mechanism controlling the latches which lock or unlock the door to the device.

In reducing my invention into practice I construct a receptacle 1 of any suitable material. This receptacle is provided with a door 2, which opens into the interior thereof, which interior is divided by means of a partition 3 into two compartments 4 and 5, respectively, the door 2 opening into compartment 4 which is the larger of the two, and which is adapted to contain a telephone instrument, which is not shown in the drawings, it not comprising a part of my invention. Mounted upon the inner face of the door are keepers 6 and 7 which have grooves therein. One of these keepers may be used if desired, but the construction is made more substantial by using two as shown. More than two may be used if conditions warrant. Pivotedly mounted upon the partition 3 are latches 8 and 9 which are provided with hooks and adapted to engage in the grooves in the keepers 6 and 7 respectively. The short arms of the latches are thickened or reinforced as at 10, as more clearly shown in Fig. 7 which construction is provided in order that the latches may be more delicately balanced so that the short arm may counter-balance the superior weight of the longer arm. A rod 11 connects the arms of the levers 8 and 9 so as to cause them to operate simultaneously.

Extended through an aperture 12 in the partition 3 is an arm 13 which may be formed integrally with the lever 9 or may be attached thereto in any desired manner. A flattened portion or plate 14 is formed upon the end of the arm 13, and is disposed immediately beneath the mouth of a chute 15 which is supported in a perpendicular po-

sition within the compartment 5 by means of brackets 16 or other suitable supporting devices.

Leading into the chute 15 are a plurality of superposed slides or coin chutes 17 which connect the slots 18 formed in the casing 1, said slots being disposed one above the other and graduated in size for different sized coins as is clearly shown in Figs. 1 and 8. 10 All of these slots are normally closed by means of a plate 19, which has an aperture 20 adapted to register with, and uncover any desired slot, said plate being slidably mounted in guide-ways 21 connected to the 15 outer face of the casing 1.

Pivotaly mounted upon a lock or arm 22 connected to the interior of the casing 1, in the compartment 5, is a lever 23, which has formed on the outer end thereof a handle 24, which handle projects through an aperture provided for the purpose in the plate 19. An elongated slot 25 is formed in the casing 1 in order to permit play of the lever 23. A spring contact 26 is connected to the 25 other end of the lever the under surface of said contact carrying a layer of insulating material 27. Mounted upon the rear wall of the casing 1 are a plurality of contact points 28 which are insulated from said wall 30 as shown. These contact points are so disposed as to be engaged by the spring contact 26 when the latter moves upward as it will do when the handle 24 is pulled downwardly. It will be seen however that when 35 said lever arm moves downwardly the insulating material 27 will come into engagement with the contact points 28 thus preventing the completion of the circuits except when the spring contact arm is moved upwardly. A spring 29 is connected to the 40 spring contact arm of the lever 23 and through the floor of the casing so as to hold said arm normally in its lowest position. It will also be seen that said spring holds the 45 handle 24 normally in its highest position, and therefore also holds the plate 19 in a corresponding position whereby all of the slots 18 are normally closed. It is of course necessary to insulate the spring contact arm 50 of the lever 23 from the handle arm, and therefore insulating material 30 is interposed between said two arms.

It is thought that the operation of my device will be sufficiently clear from the foregoing description. Supposing that five cents is to be dropped into the slot in order to gain access to the telephone instrument, it will be noted that the handle 24 must be pulled downwardly until the five-cent slot is 60 covered by the aperture 20 as shown in Figs. 1 and 2. The coin is then deposited in said slot and slides down the guide way 17 into the chute 15, and drops upon the plate 14, thus causing the latches 8 and 9 to turn upon 65 their pivots and unlock the door 2, said

latches being delicately balanced as before mentioned for this purpose. When the handle 24 is first pulled down so as to uncover the five-cent slot the spring contact 26 comes into engagement with the lowest of 70 the contacts 28.

A suitable electric circuit may be arranged whereby said contact may cause a current of electricity to indicate upon a suitable indicator at the central office the denomination of the coin deposited. When a coin of a larger denomination is to be deposited the handle 24 must be pulled lower down thus causing the spring contact to travel over two or more of the contacts 28, with the 75 result that the indicator at the central office indicates a different amount deposited for each contact 28 traveled over. As soon as the door is opened the handle 24 may be released and the spring 29 will restore the 80 plates to their initial position the insulating material 27 preventing any further electrical impulses from being transmitted to the 85 central office.

Any suitable electric circuit may be devised to accomplish the above purpose, this forming no part of my invention, but by way of illustration I have shown one form in Fig. 9. Here a conductor 31 extends from the spring contact arm of the lever 23 to a 90 suitable source of electrical energy as for instance batteries 32. Thus conductors 33 are connected to the contact 28 and extend therefrom to a suitable indicator of any desired construction, which is to be located 95 at the central office.

In order that the door 2 may be held unlocked after the operation of the latches 8 and 9 through the medium of a falling coin some sort of a latch mechanism is necessary. 105 For this purpose I show a cable 35 extending from the lever 23 downwardly through, and around a pulley 36 to a latch 37, which latch is pivotally mounted in brackets 38 which in turn are fastened to the partition 3 in 110 the compartment 4. A spring 39 holds said latch normally projected from said partition. It will be seen that the handle 24 being in a lowered position, the upward movement of the arm 10 of the latch 9 will cause 115 said arm to be engaged by means of the shoulder upon the latch 37. The door may therefore be opened. As soon as the lever 23 is restored to its normal position by means of the spring 29 the cable 35 will 120 cause said latch to release the arm 10 thus permitting the latter to fall into a position from which it will engage the keeper 7 when the door is closed.

It will be seen that I have provided a 125 very simple and effective means for containing a telephone pay station instrument such as will prevent the instrument from being used before the proper coin is deposited. It will also be noted that the parts are few 130

and that therefore the device is not likely to get out of order.

I desire it to be understood that slight changes in the construction and in the arrangement and combination of the several parts may be resorted to without departing from the spirit of my invention, provided such changes fall within the scope of the appended claims.

Having thus fully described my invention, what I claim as new and desire to secure by Letters Patent, is:—

1. In a device of the character described, a casing, two compartments in said casing, one of said compartments adapted to receive a telephone instrument, a door to said latter compartment, slots leading into the other compartment, a plate slideable on said casing adapted to normally cover said slots and means whereby said door is unlocked when a coin is dropped in any of said slots.

2. In a device of the character described, a casing having two compartments therein, one of said compartments adapted to receive a telephone instrument, a door to said latter compartment, means for locking said door when the latter is closed, slots extending into the other compartment, said slots adapted to receive coins of different denominations, a plate slideable on said casing adapted to normally cover said slots, a plate in said compartment upon which the coins are adapted to fall, and means connecting said plate and the locking mechanism of said door whereby said coins are caused to unlock said door.

3. In a device of the character described, a casing having two compartments therein, one of said compartments adapted to receive a telephone instrument, a door to said latter compartment, said door adapted to be normally in a locked position, said casing adapted to be provided with a plurality of slots, said slots adapted to receive coins of different denominations, coinways connected to said slots, one of said coinways adapted to be disposed directly above a portion of said locking means which holds said door in a locked position whereby, when a coin is inserted into said slot, it will engage said locking means and means slideable upon said casing adapted to normally close said slots, an opening formed in said last named means whereby, when said last named means is operated upon said casing said opening will register with one of said slots for the purpose described.

4. In a device of the character described, a casing having two compartments, one of said compartments adapted to receive a telephone instrument, a door to said latter compartment, means whereby said door may be locked, a plurality of slots extending into said other compartment, a plate adapted to normally cover said slots, means whereby said plate may be moved so as to uncover any desired slot, means whereby the uncovering of a slot and the depositing of a coin therein indicates to the central office the denomination of said coin, and means whereby the depositing of said coin unlocks the door to the other compartment.

5. In a device of the character described, a casing having two compartments therein, one of said compartments adapted to receive a telephone instrument, a door to said latter compartment, locking mechanism for said door, slots extending into the other compartment adapted to receive different sized coins, a plate slideable on said casing adapted to normally close all of said slots, a handle carried by said plate whereby the latter may be operated to uncover any desired slot, a lever extending from said handle into the interior of said casing, means whereby the depositing of a coin in any of said slots unlocks said door, means whereby the releasing of said handle and lever permits the locking mechanism to return to its normal position, and means whereby the operation of said handle and lever indicates to the central office the denomination of the coin deposited.

6. In a device of the character described, a casing having two compartments, a door to one of said compartments, a latch adapted to lock said door, a plurality of slots leading into the other compartment, a sliding plate adapted to normally close all of said slots, a pivoted lever in said compartment extending through said plate whereby the latter may be operated to uncover any desired slot, means whereby a coin deposited in any of said slots swings said latch upon its pivot and unlocks the door, a catch adapted to hold said latch in its unlocked position after said lever has been operated, and means whereby said catch is caused to release said latch when said lever is allowed to return to its normal position.

HERMAN IGNACIO WIECHERS.
